UNITED STATES PATENT OFFICE.

WILLIAM C. ALSMAN, OF SULLIVAN, INDIANA, ASSIGNOR TO SULLIVAN MANUFACTURING COMPANY, OF SULLIVAN, INDIANA, A CORPORATION OF INDIANA.

MINE-CAGE.

1,260,290.

Specification of Letters Patent. Patented Mar. 26, 1918.

Application filed January 19, 1918. Serial No. 212,665.

To all whom it may concern:

Be it known that I, WILLIAM C. ALSMAN, a citizen of the United States, residing at Sullivan, in the county of Sullivan and State 5 of Indiana, have invented certain new and useful Improvements in Mine-Cages, of which the following is a specification, reference being had to the accompanying drawings.

10 This invention relates to certain improvements in mine cages and it is an object of the invention to provide a novel and improved device of this general character including a tiltable platform or floor whereby a car positioned upon the platform or floor may be 15 emptied of its contents with convenience and facility.

It is also an object of the invention to provide a mine cage with novel and improved 20 means whereby a car may be effectively held upon a tiltable platform or floor and whereby such means may be engaged or disengaged from the car with facility.

The invention consists in the details of 25 construction and in the combination and arrangement of the several parts of my improved mine cage whereby certain important advantages are attained and the device rendered simpler, less expensive and otherwise 30 more convenient and advantageous for use, as will be hereinafter more fully set forth.

The novel features of my invention will hereinafter be definitely claimed.

35 In order that my invention may be the better understood, I will now proceed to describe the same with reference to the accompanying drawings, wherein:

Figure 1 is a view in side elevation of a 40 mine cage constructed in accordance with an embodiment of my invention, a car positioned thereon being indicated by dotted lines and a trip member being shown in fragment;

Fig. 2 is a view in end elevation of my 45 improved cage as herein disclosed, a car positioned thereon being also indicated by dotted lines;

Fig. 3 is a transverse vertical sectional 50 view of my improved cage as herein included with certain of the parts in elevation and the platform in its normal or horizontal position; and

Fig. 4 is a longitudinal vertical sectional 55 view taken through my improved cage with

the platform or floor in a tilted or discharging position.

As disclosed my improved cage comprises at opposite sides thereof the vertically disposed standards S and each of the standards S comprises two L-beams 1 in parallel relation and tied or connected adjacent their opposite ends by the plates 2 which serve to maintain said beams 1 in predetermined spaced relation. The flange of each of the 60 beams 1 is outwardly directed wherein a channel is afforded between said beams 1 to receive the guides (not shown) usually positioned within a mine shaft.

The upper margins of the lower plates 70 2 are provided with the inwardly directed flanges 3 upon which the side members or beams 4 of the platform or floor P are adapted to rest when said platform or floor P is in its normal or horizontal position. The 75 side members or beams 4 at substantially the longitudinal center thereof have interposed therebetween and suitably connected thereto the parallel transverse beams 5 in predetermined spaced relation and equi-distantly 80 spaced from but in close proximity to the longitudinal center of the side members or beams 4. Extending longitudinally of the platform or floor P and disposed through the end beams or members 6 of said platform or floor and through the beams 5 is the rock shaft 7. The end portions of the shaft 85 7 extend beyond the end beam 6 and secured to said extended portions are the levers or handles 8 whereby the requisite rocking 90 movement may be imparted to the shaft 7 for a purpose which will be hereinafter fully explained.

Depending from the opposite end portions of the beams 5 are the arms 9. Extending 95 between each pair or set of arms 9 is a keeper 10 having its lower portion pivotally engaged as at 11 with the lower end portions of the arms 9. The upper end portions of each of the keepers 11 is forked with the 100 fingers or arms 12 of such forked portions oppositely directed longitudinally of the platform or floor P and also disposed on a predetermined incline inwardly of the platform or floor P.

When a car C, indicated by dotted lines in Figs. 1 and 2, is properly positioned upon the floor or platform P the upper or forked ends of the keepers 10 are swung inwardly 105 to engage the wheels of the car in order 110

to maintain such car in a fixed position upon the platform or floor P. As is particularly illustrated in Fig. 1, it is to be observed that each of the keepers 10 is positioned 5 between a pair of wheels at each side of the car and the arms 12 of said keepers 10 overlie both of the wheels.

Fixed midway their length to the shaft 7 and between the beams 5 are the parallel 10 plates 14 and extending between the opposite end portions of the plates and pivotally engaged therewith as at 15 are rigid links or arms 16 extending in opposite directions having their outer end portions pivotally engaged 15 as at 17 with the keepers 10 above their pivots 11. The rigid link or arm 16 engaged with one keeper is pivotally engaged between the end portions of the plate remote therefrom as is clearly indicated in 20 Fig. 3 of the drawings. By this arrangement, it will be at once perceived that by imparting requisite rocking movement to the shaft 7 through the medium of a lever or handle 8 the keepers 10 will be moved in 25 unison, but in reversed direction so that the arms 12 thereof may be caused to engage or disengage the wheels of the car as the occasion of practice requires.

The lower end portions of the beams 1 of 30 the standards S are also connected by the plates 18 extending beyond the side of the standards S and pivotally engaged as at 19 with the extended portions of the plates are the inner end portions of the arms 20. 35 The outer end portions of the arms 20 are pivotally engaged as at 21 with the end portions of the side members 4 beyond the side of the standards S from which the extensions of the plates 18 are disposed. Each 40 of the pivots 21 also serves as a mounting for a roller 22 which is adapted to engage a trip T to cause the desired tilting of the platform or floor P when the cage has been elevated to a predetermined point. As the 45 detailed construction of the trip T forms no part of my invention, a detailed description and illustration thereof is believed to be unnecessary.

Pivotally engaged as at 23 with the beams 50 1 of the standards remote from the arms 20 are the inner end portions of the arms 24 which have their opposite end portions pivotally engaged as at 25 with the end portions of the side members or beams 4 remote 55 from the arms 20. The pivotal connections 23 are in a horizontal plane above the horizontal plane occupied by the pivots 19, but the distance between the pivots 23 and 25 is substantially equal to the distance between 60 the pivots 19 and 21. These particular relative arrangements of the arms 20 and 24 permit the tilting of the platform or floor P from the horizontal in one direction only.

When the cage is employed with passengers the holding chain 26 is employed.

One end of the chain 26 is engageable with the hook member 27 carried by the beam 1 of a standard S and at a point above the platform or floor P when in its horizontal position and the opposite end of said chain 70 26 is engageable with the hook member 28 carried by the side member or beam 4 at a point adjacent a roller 22.

The upper end portions of the beams 1 have interposed therebetween and suitably 75 connected thereto the beams 29 arranged in parallelism and disposed transversely of the platform or floor P. The hoisting cable (not shown) is adapted to be engaged with said beams in a conventional manner. The 80 beams 29 have disposed therefrom in opposite directions and adjacent their ends, the supporting frames 30 to afford a support for the roof or top 31 extending beyond opposite sides of the standards S and in a direction longitudinally of the platform or 85 floor P.

The space between the beams 29 adjacent the opposite ends thereof is intersected by the members 32 supported by the beams 29. 90 The members 32 are directed through the longitudinally disposed slots 33 produced in the outer end portions of the safety dogs 34. The inner end portions of the dogs 34 are pivotally engaged as at 35 with the upper 95 standing clevis 36 which is adapted to be suitably secured, with the hoisting cable. Engaged with the pivots 35 between the dogs 34 is the upper end portion of the depending arm 37. The lower end portion 100 of the arm 37 is suitably connected at substantially the longitudinal center of a semi-elliptical spring 38. The extremities of the spring 38 contact with the end faces of the dogs 34 outwardly of the members 33 so 105 that in the event of the hoisting cable breaking, the dogs 34 will be automatically forced outwardly to engage the guides, not shown, to prevent the dropping of the cage.

From the foregoing description, it is 110 thought to be obvious that a mine cage constructed in accordance with my invention is particularly well adapted for use by reason of the convenience and facility with which it may be assembled and operated and it 115 will also be obvious that my invention is susceptible of some change and modification without departing from the principles and spirit thereof and for this reason I do not wish to be understood as limiting myself to 120 the precise arrangement and formation of the several parts herein shown in carrying out my invention in practice except as hereinafter claimed.

I claim:

1. A mine cage comprising a pair of standards, means for maintaining said standards in predetermined spaced relation, a tiltable platform disposed between the standards, members carried by the standards 125 130

- upon which the platform rests when in substantially a horizontal position, arms pivotally connected with the standards below the platform and pivotally engaged with an end portion of the platform, a second set of arms pivotally engaged with the opposite end portions of the platform and with the standards at a point above the pivotal connection between the standards and the first named arms, and detachable means coacting with the platform and a standard for holding the platform against tilting movement when in substantially horizontal position.
- 5 2. A mine cage comprising a pair of standards, means for maintaining said standards in predetermined spaced relation, a tilttable platform disposed between the standards, members carried by the standards upon which the platform rests when in substantially a horizontal position, arms pivotally connected with the standards below the platform and pivotally engaged with an end portion of the platform, and a second set of arms pivotally engaged with the opposite end portions of the platform and with the standards at a point above the pivotal connection between the standards and the first named arms. 20 25
- 10 15

In testimony whereof I hereunto affix my 30
signature.

WILLIAM C. ALSMAN.
